UNITED STATES PATENT OFFICE.

JOHN JOS. HOFFMAN, OF DENISON, IOWA.

DESIGN FOR A BRACKET.

SPECIFICATION forming part of Design No. 23,969, dated January 29, 1895.

Application filed November 15, 1894. Serial No. 528,927. Term of patent 14 years.

To all whom it may concern:

Be it known that I, JOHN JOSEPH HOFFMAN, of Denison, in the county of Crawford and State of Iowa, have invented and produced a new and original Design for a Bracket, of which the following is a specification.

Reference is to be had to the accompanying drawing, forming a part of this specification, in which the figure represents in perspective a bracket embodying my new design.

The leading feature of my design consists in a bracket, having on its face transverse

flutings *a* and non-fluted surfaces *b* at each side of such fluted surface, said fluted and non-fluted surfaces ranging longitudinally 15 along the face of the bracket.

I claim—

The design for a bracket herein shown and described.

JOHN JOS. HOFFMAN.
